UNITED STATES PATENT OFFICE.

ELIJAH B. BENHAM, OF GROTON, AND CHARLES R. WATROUS, OF LEDYARD, CONNECTICUT; SAID BENHAM ASSIGNOR TO SAMUEL A. WHIPPLE AND SILAS S. WHIPPLE, OF LEDYARD, CONNECTICUT.

NUT-CRACKER.

SPECIFICATION forming part of Letters Patent No. 322,240, dated July 14, 1885.

Application filed February 18, 1885. (No model.)

To all whom it may concern:

Be it known that we, ELIJAH B. BENHAM, of Groton, New London county, in the State of Connecticut, and CHARLES R. WATROUS, of Ledyard, in the county and State aforesaid, have invented certain new and useful Improvements in Nut-Crackers, of which the following is a specification.

Our improved nut-cracker applies the force of the hand at a great mechanical advantage or purchase and in an oblique direction, so as to throw the crushing-surfaces past each other. The surfaces between which the nut is compressed are peculiarly arranged to facilitate the adaptation of the instrument to nuts of various sizes. The arrangement allows the repetition of compression by shifting the nut each time into a narrower portion of the space between the jaws.

The accompanying drawings form a part of the specification, and represent what we consider the best means of carrying out the invention.

Figure 1 is a side elevation. Fig. 2 is a plan view. Fig. 3 is a cross-section on the line $\alpha\alpha$ in Figs. 1 and 2, looking in the direction of the arrow.

Similar letters of reference indicate corresponding parts in all the figures where they occur.

A is the body, and A' the jaw thereon. A² is the handle. These parts A A' A² are a single malleable-iron casting.

B is the counter-lever, and B' the counter-jaw. B and B' are a single malleable-iron casting. It turns on a rivet, b, inserted in the body A at the point represented.

C is a spring of flat steel, clamped in a thin recess produced by sawing or otherwise in the jaw A', and acting on the counter-lever B to depress it.

D is the operating-lever. It turns on an axis formed by a pivot, d, cast on its side and engaged in a socket in the body A at the point indicated by dotted lines in Fig. 1. This operating-lever D acts on the counter-lever B at the point B*. The counter-lever

B is formed with a ridge on its edge, which is engaged by a lip, A³, on the body, so that it is steadied in its up and down motion as it is raised by the operating-lever D, acting at the point B*, and is pressed down by the spring C.

The surfaces of the jaws A' and B', which are presented toward each other, are wide and ridged, so as to prevent the slipping of the nuts to be cracked as they are successively introduced and compressed between them. The working-faces are each nearly plane. They are inclined, as shown, in both directions—that is to say, in the vertical direction they diverge upward, and in the horizontal direction they diverge from the right toward the left.

The whole constitutes a small and conveniently portable implement, bringing great power to bear on the nut. We attach importance to the position of the working-faces of the jaws, and particularly to the motion. The pivot b, on which the counter-lever B B' swings, is so related to the working-faces and the handles that said faces change their positions relatively to each other, and thus change the point of contact on the nut as the handles D A² are forced together.

Modifications may be made in the forms and proportions. Instead of the peculiar pivot d, an ordinary rivet may be inserted in the body. We prefer the construction shown, as economical in first cost and peculiarly strong and reliable.

The spring C may be confined in the saw-kerf, in which it is set by one or more blows on a set properly applied adjacent to the kerf while the spring is held in position.

The surfaces may be left unfinished or may be variously coated or decorated. They may be polished, plated with nickel or other metal, or japanned.

We claim as our invention—

1. In a nut-cracker, the combination, with the jaw A A' A² and the lever B, pivoted at b and carrying jaw B', of the operating-lever D, all arranged to serve as set forth.

2. In a nut-cracker, the jaws A' B, having working-faces inclined and corrugated in two directions, and the lever B, pivoted at *b* to the body, and having shoulder B* and the handle D, all combined and operating as and for the purposes set forth.

In testimony whereof we have hereunto set our hands, at Mystic River, Connecticut, this

6th day of February, 1885, in the presence of two subscribing witnesses.

E. B. BENHAM.
CHARLES R. WATROUS.
